UNITED STATES PATENT OFFICE

93,800

DESIGN FOR A TROLLING SPOON

Erick Sylvan, Astoria, Oreg.

Application August 22, 1934, Serial No. 53,020

Term of patent 14 years

To all whom it may concern:

Be it known that I, ERICK SYLVAN, a citizen of the United States, residing at Astoria, in the county of Clatsop, and State of Oregon, have invented a new, original, and ornamental Design for a Trolling Spoon, of which the following is a specification, reference being had to the accompanying drawing, forming part thereof.

Figure 1 is a view in top plan of a trolling spoon, showing my new design.

Figure 2 is a bottom plan view thereof.
Figure 3 is a side elevational view.
Figure 4 is a rear end elevational view.
Figure 5 is a front end elevational view.
I claim:—
The ornamental design for a trolling spoon as shown.

ERICK SYLVAN.
